UNITED STATES PATENT OFFICE.

FRANK O. WOOD, OF BROWNSVILLE, WISCONSIN, ASSIGNOR OF ONE-HALF TO LESTER NATHANIEL PHELPS, OF FOND DU LAC, WISCONSIN.

STANCHION.

1,088,862.

Specification of Letters Patent. Patented Mar. 3, 1914.

Application filed September 22, 1913. Serial No. 781,148.

To all whom it may concern:

Be it known that I, FRANK OSCAR Wood, a citizen of the United States, residing at Brownsville, in the county of Dodge and State of Wisconsin, have invented certain new and useful Improvements in Stanchions; and I do declare the following to be a full, clear, and exact description of the invention, such as will enable others skilled in the art to which it appertains to make and use the same.

This invention relates to stanchions, and the object of the same is to effect improvements in the means whereby the hinged yoke member is held closed or permitted to open.

With this end in view the invention consists of certain novel features of construction, and the combination and arrangement of parts as will be more fully described and claimed.

In the accompanying drawings: Figure 1 is a front view of my improved stanchion showing the latter in closed position; Fig. 2 is a top plan view thereof; Fig. 3 is a front view of the stanchion with parts of the upper supporting bars removed and illustrating the position of the stanchion when open; Fig. 4 is a vertical cross section of the stanchion taken on the line 4—4 of Fig. 1; Fig. 5 is a detail horizontal section through the stanchion operating mechanism and the upper end of the stanchion taken on the line 5—5 of Fig. 3; Fig. 6 is a view similar to Fig. 1 showing two stanchions arranged in series and illustrating the manner in which one of the same is held in closed position while the other is opened by the operating mechanism. Fig. 7 is a similar view illustrating the manner in which one or more of the stanchions may be independently opened without opening the rest of the stanchions in the series; Fig. 8 is a horizontal sectional view of one of the stanchions and its supporting mechanism taken on the line 8—8 of Fig. 3; Fig. 9 is a detail perspective view of the lever for operating the stanchion fastening and releasing mechanism and the link which connects the lever thereto; Fig. 10 is a similar view of one of the independent stanchion locking and releasing devices; Fig. 11 is a similar view of one of the stanchion supporting blocks the parts thereof being separated.

Referring more particularly to the drawings, 1 denotes the base or coping on which my improved stanchions are supported and

which may be formed of wood, concrete or any other suitable material. Spaced suitable distances apart and secured at their lower ends in the base or coping 1 are a series of supporting standards 2 to the upper ends of which are secured upper stanchion supporting bars 3 which are preferably in the form of angle iron bars as shown. Bolted or otherwise rigidly secured between the bars 3 at a point substantially midway between the upper ends of the standards 2 is a stanchion supporting block 4 which is formed in two sections each of which has its upper end offset to form a bearing lug 5, 70 said lugs having in their inner sides semi-circular recesses which when the lugs are brought together will register and form a bearing opening for the upper end of the stanchion whereby the latter is loosely supported as will be hereinafter more fully described. 75

The neck engaging portion or yoke of the stanchion comprises a stationary member 6 and a hinged or opening member 7. The 80 stationary member 6 of the yoke has on its upper end an upwardly projecting supporting stud 8 having on its upper end a head 9. The stud 8 for a short distance below the head is cylindrical and below the cylindrical portion the stud is semi-cylindrical as shown. The cylindrical portion of the stud has a pivotal or revoluble engagement with the bearing aperture in the lug 5 of the block 4 whereby the upper end of the yoke 90 is revolvably and loosely supported to permit the yoke to swing freely in all directions and to revolve between the standards 2. Formed on the upper end of the pivoted member 6 of the yoke at the lower end of the stud 8 are a pair of laterally projecting apertured lugs 10 the purpose of which will be hereinafter described. 95

The opening member 7 of the yoke has a hinged connection at its lower end with the 100 lower end of the stationary or pivoted member 6 with which it co-acts to form the yoke. The upper end of the member 7 when in a closed or operative position engages between the laterally projecting lugs 10 on the upper end of the member 6 and is thereby held in engagement with or against lateral movement at its upper end. Formed on the upper end of the member 7 is an upwardly projecting semi-cylindrical stud 11 which 110 when the member 7 of the yoke is in closed position, engages the semi-cylindrical por-

- tion of the stud 8 on the member 6. The stud 11 projects between and has a sliding engagement with the bars 3 when the member 7 is swung to an open or closed position.
- 5 The members 6 and 7 of the yoke are preferably formed of metal and have secured to their inner sides lining strips 12 which provide a smooth surface for engaging the necks of the animals fastened by the stanchion.
- 10 The yoke is loosely connected at its lower end to the base or coping 1 by chains 13 the upper ends of which are connected to the lower ends of the members 6 and 7 of the yoke, while the lower ends of the chains 15 are preferably connected to an eye bolt 14 which has a swiveled connection with a fastening plate 15 secured to the top of the base or coping 1 midway between the standards 2 as shown. By thus connecting the 20 lower end of the yoke to the coping 1 the yoke is permitted to swing freely in all directions.
- Slidably mounted on the upper supporting bars 3 of the stanchion is a yoke opening and closing mechanism comprising a pair of bars 16 which are preferably formed of angle iron and which are spaced apart the same distance as the bars 3 and have a sliding engagement therewith. The bars 25 16 extend the entire length of the bars 3 and row of stanchions supported thereby and secured between the bars 16 adjacent to one side of the space between the standards 2 of each of the stanchions is a spacing block 17 having formed integral therewith a depending bracket 18 which extends downwardly between the bars 3 and between the block 4 and the adjacent standard 2 for a purpose hereinafter described. Pivotally 30 secured between the bars 16 adjacent to and spaced a suitable distance from the studs 8 and 11 on the upper end of the yoke is a combined stop and yoke closing and releasing member 19 which is in the form of a block having on the lower side of its free 35 end a depending lug 20 which, when the block is in a closed and operative position projects downwardly between the bars 3 and in position to engage the upper end of the stud 11 or the hinge member 7 of the 40 yoke. The end of the block and adjacent end of the lug 20 have formed therein a vertical groove or notch 21 which receives the rounded outer side of the stud 11. On the 45 upper side of the block 19 is secured a plate 22 the ends of which project beyond the sides of the block and engage the upper edges of the bars 16 when the block is swung downwardly to an operative position and thereby limit the downward movement of the block. By thus arranging the block or member 19 it will be seen that when the bars 16 are shifted in one direction on the bars 3, the block 19 and lug 20 will be 50 moved back or away from the studs 8 and 10 of the yoke members and will thus permit the member 7 to swing outwardly or away from the member 6 to an open position as is clearly shown in Fig. 3 of the drawings. When the bars 16 are shifted in the opposite direction the engagement of the lug 20 with the stud 11 will swing the member 7 of the yoke back to a closed position in which position the member 7 will remain until the bars 16 are again shifted to open the yoke.
- The bars 16 are shifted to open and close the yokes of the stanchions by a lever 23 having a right angular offset inner end which is pivotally secured to the upper end 55 of the standard 2 at one end of the row of stanchions and which is connected by a pair of diverging links 24 to the adjacent end of the bars 16 whereby when the lever is swung upwardly, said bars 16 and the blocks 19 carried thereby will be shifted in the proper direction for permitting the members 7 of all of the yokes in the row of stanchions to swing to open positions. When the lever is swung downwardly the bars 16 and block 19 will be shifted in a reverse direction which will cause the lugs 20 on the blocks 19 to swing the hinged members 7 of the entire row of yokes to a closed position.
- Should it be desired to prevent the opening of one or more of the yokes at any place along the line of stanchions and thus prevent the releasing of the animals fastened thereto, I provide stop pins 25 which are engaged with aligned apertures 26 formed in the bars 3 adjacent to the outer sides of the studs 11 when the latter are in closed position, said pins thus holding the studs 11 in engagement with the studs 8 and preventing the opening movement of the yoke members 7 when the bars 16 and block 19 are shifted to release the hinged members of the other yokes in the manner described.
- When it is desired to release one or more of the animals at any point along the line of stanchions without releasing the entire row it is simply necessary to swing the block 19 and the lug 20 upwardly from between the bars 3 and above the bars 16 as clearly shown in Fig. 7 of the drawings whereupon the hinged member 7 of this yoke will be permitted to swing back to an open position. When the members 7 are thus swung open, the opening movement thereof is limited by the engagement of one of the pins 25 with aligned apertures 27 which are also formed in the bars 3 a suitable distance from the apertures 26. When the pin 25 is thus arranged the stud 11 on the outer end of the yoke member 7 will engage the pin which will limit the opening movement of said member as will be readily understood.
- In order to prevent the animals when entering the stalls from passing or project-

ing their heads through the space between the pivoted or stationary member 6 of the yokes and the adjacent standard 2 of the stanchions, when the yokes are in an open position, I preferably provide a stop or closing member for this space, said member being in the form of a vertical post or standard 28 which preferably corresponds to the standards 2 to which the post 28 is hingedly attached by means of upper and lower supporting arms 29 and 30, said arms having in their inner ends apertures which receive the standard 2 and in their outer ends sockets 31 which receive the ends of the posts 28, said posts being secured in the sockets in any suitable manner. On one side of the upper arm 29 is formed an offset apertured lug 32 to which is pivotally attached one end of a segmental post operating plate or link 33, the opposite end of which is pivotally connected to the lower end of the depending bracket 18 of the spacing block 17 whereby when the latter is shifted by the bars 16 when said bars are moved to permit the yokes to open, said links 33 will swing the arms 29 and 30 and the post 28 inwardly, thus bringing the latter to a position between the stationary member 6 of the yoke and the adjacent standard 2 which will effectually prevent the animal from passing or inserting its head through this space.

The position of the member 7 when open will prevent the animal from passing or projecting its head through the space between this side of the yoke and the adjacent standard 2 so that the animal must of necessity pass its head through between the members 6 and 7 of the yoke and in position to be fastened when the movable member is drawn back to a closed position as will be readily understood. When the bars 16 are shifted to bring the members 7 back to a closed position, the movement of the block 17 and bracket 18 will through the link 33 again swing the arms 29 and 30 and the post 28 out of the space between the members 6 of the yoke and the adjacent standard 2 thus leaving this space open to permit the yoke to swing freely between the standards as the animal moves its head from side to side.

From the foregoing description taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of the invention as claimed. 60

Having thus described my invention, what I claim is:

1. A stanchion comprising a base, standards secured thereto, yoke supporting bars secured to said standards, a block secured to 65 said bars and having a bearing, a yoke comprising a stationary member having at its upper end a stud pivotally mounted in said bearing, an opening member hinged to said stationary member and having at its upper 70 end a stud projecting between said supporting bars, a yoke operating member having a sliding engagement with said supporting bars, a block pivotally mounted in said yoke-operating member and having a lug adapted 75 to pass between said supporting bars, the face of the lug being provided with an upright groove adapted to engage the stud on the upper end of said hinged member when the lug is lowered or to disengage said stud 80 when the block is raised, and means to limit the outward movement of said hinged yoke member and to fasten the latter in a closed position.

2. A stanchion comprising a base, standards rising therefrom, yoke supporting bars secured to said standards, a block secured between said bars, a yoke comprising a stationary member having a loose pivotal connection with said block, an opening member 90 hinged at its lower end to said stationary member and having at its upper end a stud projecting between said bars, a yoke operating mechanism comprising a pair of bars 95 slidably mounted on said yoke supporting bars and means for moving them, a block pivoted between said yoke operating bars and adapted when in an operative position to engage said stud, and a plate secured across the top of said block and projecting 100 beyond its sides to rest upon the yoke operating bars when the block stands in this position.

In testimony whereof I have hereunto set my hand in presence of two subscribing witnesses. 105

FRANK O. WOOD.
